(57) **CLAIM**

The ornamental design for a patient interface, as shown and described.

DESCRIPTION

FIG. 1 is a perspective view of a patient interface showing a first embodiment of our ornamental design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a patient interface showing a second embodiment of our ornamental design;

FIG. 9 is a front view thereof;

FIG. 10 is a rear view thereof;

FIG. 11 is a top view thereof;

FIG. 12 is a bottom view thereof;

FIG. 13 is a left side view thereof;

FIG. 14 is a right side view thereof;

FIG. 15 is a perspective view of a patient interface showing a third embodiment of our ornamental design;

FIG. 16 is a front view thereof;

FIG. 17 is a rear view thereof;

FIG. 18 is a top view thereof;

(Continued)

FIG. 19 is a bottom view thereof;
FIG. 20 is a left side view thereof;
FIG. 21 is a right side view thereof;
FIG. 22 is a perspective view of a patient interface showing a fourth embodiment of our ornamental design;
FIG. 23 is a front view thereof;
FIG. 24 is a rear view thereof;
FIG. 25 is a top view thereof;
FIG. 26 is a bottom view thereof;
FIG. 27 is a left side view thereof; and,
FIG. 28 is a right side view thereof.

One or more views (e.g., bottom view) may not be shown as those views are unornamented or simply not claimed in a given embodiment.

The broken lines represent portions of the patient interface and do not form part of the claimed design.

The combination of line shading, stippling, and textile/fabric if any, is intended to convey a contrast in appearance/materials.
